IRONING MACHINE CABINET

Andrew H. Gerhardt, Chicago, Ill., assignor to
Electric Household Utilities Corporation, Chi-
cago, Ill., a corporation of Illinois

Application August 13, 1937, Serial No. 158,884

3 Claims. (Cl. 312—190)

This invention relates to cabinet constructions of the type including a table-like support on which an instrument or a like unit is mounted, and more particularly, to constructions of the type including suitable means permanently associated with the support for enclosing the instrument or unit.

Heretofore, covers or closure means for cabinets of the general character indicated have generally been formed as inverted box-like structures, preferably including a substantially flat top adapted to serve as an auxiliary supporting surface. Such closures or covers usually have been formed as a unitary element, and frequently the dimensions thereof are such as to render handling thereof rather awkward and difficult, particularly when the closures or covers are of the type that are adapted for bodily removal from the table-like support. In some commercial forms of apparatus of this general class, the cover or closure means is associated with the table-like support in a manner for permitting pivotal movement thereof to and from operative position. In some of such constructions, the cover or closure means, when removed to expose the instrument or like unit, is compelled to occupy a space immediately rearwardly of the table-like support, or at one end thereof. Manifestly, when apparatus, having such types of closures, are positioned in close proximity to a wall or other objects, it is first necessary to move them a sufficient distance to provide adequate clearance for accommodating the cover or closure means, when same is moved to expose the instrument or unit.

One of the primary objects of the present invention resides in the provision of a novel and improved form of closure means of the character indicated, which is constructed and arranged to obviate the foregoing objections, and which may be quickly and conveniently manipulated for exposing or enclosing an instrument or like unit on a table-like support.

Another object of this invention is to provide an improved closure means of the character indicated wherein said closure means is composed of a pair of end panels associated with a pair of opposed ends of the table-like support, together with a flexible cover element adapted to be moved into and out of cooperation with said end panels for enclosing the instrument or exposing same for use.

A further object is to provide an improved closure means for apparatus of the character indicated comprising a flexible cover element adapt-

ed for cooperation with a pair of end panel elements, hingedly associated with the ends of the table-like support, and adapted to normally extend in upright position, to constitute a portion of the closure means, but which are also adapted, when the flexible cover is withdrawn, to be swung outwardly and downwardly substantially in horizontal position, to constitute a shelf or extension for the top of the said table support.

Other objects and advantages of this invention will be apparent from the following description, taken in connection with the accompanying drawings, in which:—

Fig. 1 is a perspective view of a table-like support and closure means constituting the present invention.

Fig. 2 is a rear view of the table-like support with the closure means in inoperative position, exposing the instrument or like unit.

Fig. 3 is a plan view of the table-like support and closure means.

Figs. 4 and 5 are enlarged transverse sections, taken as indicated at line 4—4 and line 5—5 respectively on Fig. 1.

Fig. 6 is a transverse sectional view through the flexible cover, taken at line 6—6 on Fig. 1.

Fig. 7 is a section through the flexible cover taken as indicated at line 7—7 on Fig. 4.

Fig. 8 is a staggered horizontal section through the table-like support and closure, taken as indicated at line 8—8 on Fig. 1, showing latching means for releasably securing one of the end panels of the closure means in upright position.

Fig. 9 is a vertical sectional view, taken as indicated at line 9—9 on Fig. 8.

Fig. 10 is a view similar to Fig. 8, showing a modified form of latching means.

Fig. 11 is a section through the modified form of latching means, taken as indicated at line 11—11 on Fig. 10.

Referring now in detail to the drawings, I have herein illustrated the present invention in connection with a table-like structure on which is mounted a conventional ironing machine of the character usually employed in the home. It will be manifest, however, that the present invention is readily adaptable to various other types of cabinet constructions for enclosing a wide variety of instruments or like units, when mounted on a table-like support.

The construction herein illustrated includes a table-like support of generally rectangular form preferably fabricated of sheet metal and comprising a top 10, and end supports herein shown formed as panels 11, the vertical edges of which 55

are bent angularly for purposes of reinforcement, and also to serve the function of leg members. The marginal edge of said top is formed with a depending reinforcing flange or skirt 10^a, 5 which is adapted to over-lie said end panels, and rigidly secured thereto in any convenient manner, such as by welding. Secured to the lower portions of each of said end panels is a horizontally disposed reinforcing element 12, the 10 rearward ends of which are connected and reinforced by a tie member 13. Secured in the corners formed by the angularly bent portions of the respective end panels, are brackets 14, constituting sockets for conventional caster 15 wheels 15. Mounted on the support top 10, I have shown a conventional ironing machine, designated generally at A, the dimensions of which are such as to lie within the marginal edges of said top 10.

20 The means for enclosing the ironer unit, and constituting the present invention, is preferably constructed and formed so that in closed position it presents a substantial flat top area, which may be used as an auxiliary supporting surface. Said 25 closure means include a pair of swingable end panel members 20, which are normally disposed in upright position at the ends of the table top 10, and are connected to said table-like support in a manner to permit disposition of said panels 30 in a substantially horizontal plane, with the upper surface thereof approximately flush with the table top 10, as seen in the drawings, and thereby constitute auxiliary shelves or extensions for said table top. Such shelves or extensions, in 35 connection with various types of instruments or units, and particularly with ironing machines, are of considerable importance, in that they provide adequate auxiliary supporting surfaces for fabrics to be ironed, or fabrics that have been ironed, or for supporting various apparatus used 40 in connection with the ironing operation, such as a pan of water, sponge, or spraying device. For purposes of appearance and economy in manufacture, said end panels 20 are of similar construction, and are formed of sheet metal, fabricated in a manner to produce a substantially closed hollow body providing two spaced apart 45 substantially parallel panel surfaces. As will hereinafter appear, said panels are so connected to the table-like support, that in upright closing position, the one main surface thereof is substantially flush with the end panels 11 of the table-like support, and in operating position, that is, when disposed in horizontal position, as a shelf, 50 the opposite surface of the end panels 20 are positioned substantially flush with the top 10 of the table-like structure.

The outer marginal edges of each of the end panels 20 are formed in a manner to provide a 55 continuous track or guideway 21, around the free marginal edge thereof. The tracks are each composed of two straight vertical portions, and a straight horizontal portion at the upper edge, the latter being joined to the former by arcuate portions. A flexible cover element 23 has its opposite marginal edges terminating in a plane for movement into the tracks 21, of the end panels 20, when said panels are in upright position, to 60 complete the closure for enclosing the ironer unit or other instruments or units.

For convenience in moving the flexible cover to and from cooperative relation with said end panels 20, I provide a pair of spaced apart handles 24, adjacent the foremost edge of said 65 cover element. If desired, the flexible cover may

be formed of a single sheet of flexible material, preferably metal, or as herein shown, it may be composed of a multiplicity of parallel metal slat-like members 25, flexibly connected together in any suitable manner, to form a unitary body. In order to utilize relatively light weight sheet metal for fabricating these slats, for purposes of economy and lightness in weight to render the moving of the cover to and from operative position as convenient and as practical as possible, said slat elements are connected by a plurality of transversely spaced apart reinforcing members 28. For this purpose, the slat elements 25 each have their marginal longitudinal edges down turned to form flanges 29, and formed in said flanges are aligned series of apertures 30, for receiving said members 28, which serve to connect and reinforce said slat elements. The flanges 29 at the ends of the slats are preferably cut away to fit conveniently in the guideways. It will be apparent, however, that if desired these slat like members 25 may be directly interconnected in a manner to provide adequate flexibility.

Secured to the angularly bent portions of the rear side of end panels 11 of the table-like structure, are a pair of upright guides 26, each having its marginal outer edge folded back upon itself in spaced-apart relation to form a guideway 26^a, with which may be aligned the guideways 21 of the panels 20, for receiving and guiding the marginal vertical edges of cover 23 in its movement to and from closing position. As may be seen in Fig. 5, the rear portion of guideways 21 of panels 20, are formed of sufficient width to accommodate said folded marginal portions of the guides 26. Secured by bolts 27^a to the inside surface of said guides 26 is a transversely extending panel 27, preferably of sheet metal, which serves to reinforce the structure and also conceal the underside of the cover element when it is disposed in open position, as may be seen in Figs. 2 and 3. By virtue of this construction the flexible cover 23 may be quickly and easily moved in its guides to closed position for enclosing the ironer or other unit, or may be moved downwardly and rearwardly, as in Fig. 2, to afford free access to said ironer.

The end panels 20 are releasably latched in upright position and for this purpose each of said panels is provided with a pair of transversely spaced apart bars 32, which are rigidly attached to the interior of said panels, by means of screws 33, as seen in Fig. 9. Said bars each include a depending leg portion projecting downwardly from said panels through apertures 10^b, formed in the top and skirt portion 10^a of the table top 10, and are provided with transversely extending pins 35, immediately below said slots, to preclude withdrawal of the depending leg portions of the members 32 from the table-like structure. These pins 35 are so located as to enable the bottom edge of the end panels 20 to normally rest upon the top of the table 10, while also permitting said edge to ride around the rounded marginal edge of the top 10, for disposition flatly against the skirt portion 10^a of the table top, as indicated in dotted lines in Figs. 9 and 11. Desirably, the depending portions of the legs 32 are formed with offset portions 32^a and 32^b, the portions 32^a serving to abut against inner surface of upper portion 70 of the end panels 11 of the table-like support, to serve as stops for arresting the panels 20 in vertical or upright position, as seen in Fig. 9. The offset portions 32^b are adapted, when the end panels 20 are disposed in horizontal position, to 75

serve as a stop for abutment against the under-side of the table top 10, for arresting and supporting the panels 20 in a horizontal position, with the upper surface flush with the table top 10.

5 The end panels 20 are normally latched in upright position but may be easily and quickly released for disposition in horizontal plane to serve as a shelf. For convenience, I provide separate latching means for each of the end panels, although it will be apparent that a single operating mechanism may be arranged for controlling the latches simultaneously. Rigidly secured by screws 38 in the inturned angularly bent portions of each of the end panels 11 are a pair of aligned 10 bearings 39, providing journaled support for transversely disposed rock shafts 40. Rigidly attached to each shaft, by means of pins 41 are a pair of horizontally extending latch bars 42, the outer ends of which are notched as indicated at 15 43, to provide seats for receiving the lower ends of the respective legs 32, which constitute the hinge connection for the end panels, as seen in Fig. 9. Each rock shaft 40 is normally urged in a direction for raising the latch bars 42 by means 20 of a coil spring 44 surrounding the shaft intermediate one of the bearings 39, and the adjacent latch bar 42, with one end of the spring disposed beneath said latch bar and its opposite end engaged in the bearing 39. Each shaft 40 is adapted 25 to be separately rocked to depress the latch bars 42 and thereby release the corresponding leg portions 32 to permit disposing the respective end panels 20 in horizontal position. This may be accomplished by means of a compressible plunger 45, 30 which extends upwardly through the table top 10, having its upper end provided with a convenient hand knob 46. Each of said plungers is journaled in a bushing 47, secured in the table top 10 and is dimensioned so that its lower end normally 35 rests upon a transversely extending pin 49, extending laterally from the adjacent latch bar 42. It will now be apparent that when the plunger is depressed to the dotted position indicated in Fig. 45 9, the corresponding latch bars 42 will be rocked to the dotted position, as seen in Fig. 9, removing the seats 43 from engagement with said leg members, 32, at which time said leg members are released to permit the corresponding end panel 20 to be moved outwardly and downwardly to horizontal 50 position. Due to the particular construction herein illustrated, it will be apparent that as the end panel 20 is again swung upwardly to operative position, the lower end of the leg members 32 wipe over latch bars 42, and automatically 55 become latched by said latch bars 42, which are normally urged in an upwardly direction by the coil springs 44.

Figs. 10 and 11 represent a modified form of releasable latching mechanism. In this construction the end panels 20 are hingedly attached to the table top 10 in a manner similar to that above described, and for convenience the latch mechanism at one end only will be described. The hinge connection to the end panel 20 includes a pair of transversely spaced apart leg members 50 secured by screws 51, interiorly of the end panel; the portion of the leg projecting downwardly from the end panel 20 includes offset portions, 50^a, 50^b, and 50^c, the portions 50^a and 50^b serving respectively as stops in the same manner as the portions 32^a and 32^b in the construction disclosed in Figs. 8 and 9, while the lower end portion 50^c is adapted to be engaged by a modified form of latching device.

75 Mounted on the inner surface of the end wall

of the end panel 11 of the table-like support, by means of screws 52, are a pair of transversely spaced apart brackets 53, in which is slidably mounted a horizontally extending operating bar 54, to which is rigidly attached a pair of latching members 55, formed with angularly bent hook portions to embrace the lower portions 50^c of the legs 50, for securing the end panel 20 in upright position. Said sliding bar 54 is normally urged in a direction to cause the latches 55 to engage said lower portions 50^c of the hinged legs, by means of a coil spring 56, which is connected by means of a bolt directly to the end panel 11 at one end, and at its opposite end to an operating handle 57, which is rigidly attached, as by welding, to the slide bar 54. When the slide bar 54 is shifted by means of the handle 57 to the dotted position, indicated in Fig. 10, the bar 54 is moved to cause latches 55 to release the lower portions 50^c of the hinge legs so that the end panel may be swung 20 downwardly to horizontal position, as indicated in dotted lines in Fig. 11. The latching members 55 are each formed with a bevelled end portion 55^a so that when the end panel is swung upwardly to operating position, the portions 50^c at the lower 25 ends of the leg members 50 are caused to engage the latch portions 55^a in a cam-wise manner, for moving the latches, together with the bar 54 to a position at which the latches 55 may effectively embrace the lower portions of the hinge legs 50, 30 and thereby lock the end panel 20 in upright position.

Although I have herein shown and described a preferred embodiment of my invention, manifestly it is capable of modification and rearrangement 35 of parts without departing from the spirit and scope thereof. I do not, therefore, wish to be understood as limiting this invention to the precise embodiment herein disclosed, except as it may be so limited by the appended claims.

I claim:

1. The combination with a table-like support including a top formed of sheet metal and having down-turned marginal flanges at opposite ends, and an instrument or like unit mounted on said top; of means carried on the support for enclosing said instrument or unit, said means comprising a pair of normally upwardly extending panels on the opposite ends of said support, a bodily movable flexible cover element, and means on the back of the table-like support for guiding and supporting the flexible cover element, said cover element and end panels being constructed for cooperative engagement for completing the closure, said end panels having their lower ends provided with a floating hinge connection disposed inside of the support, and adapted, when the cover element is moved to inoperative position, to be swung outwardly and downwardly to substantially horizontal position, in substantially flush 60 relation with and constituting extensions of the table top, said hinge connections for each end panel including a pair of spaced apart bars projecting downwardly from the panel, through apertures in the table-like support, and adapted in 65 one position to engage an abutment surface of the support to arrest the end panel in upright position.

2. The combination with a table-like support including a top formed of sheet metal and having down-turned marginal flanges at opposite ends, and an instrument or like unit mounted on said top; of means carried on the support for enclosing said instrument or unit, said means comprising a pair of normally upwardly extend-

ing panels on the opposite ends of said support, a bodily movable flexible cover element, and means on the back of the table-like support for guiding and supporting the flexible cover element, said cover element and end panels being constructed for cooperative engagement for completing the closure, said end panels having their lower ends provided with a floating hinge connection disposed inside of the support, and adapted, when the cover element is moved to inoperative position, to be swung outwardly and downwardly to substantially horizontal position, in substantially flush relation with and constituting extensions of the table top, said hinge connections for each end panel including a pair of spaced apart bars projecting downwardly from the panel, through apertures in the table-like support, and adapted in one position to engage an abutment surface of the support to arrest the end panel in upright position, and adapted to engage another abutment surface of the support to arrest and dispose the end panel in substantially horizontal position, substantially flush with the top.

3. The combination with a table-like support including a top formed of sheet metal and having down-turned marginal flanges at opposite ends, and an instrument or like unit mounted on said top; of means carried on the support for enclos-

ing said instrument or unit, said means comprising a pair of normally upwardly extending panels on the opposite ends of said support, a bodily movable flexible cover element, means on the back of the table-like support for guiding and supporting the flexible cover element, said cover element and end panels being constructed for cooperative engagement for completing the closure, said end panels having their lower ends provided with a floating hinge connection disposed inside of the support, and adapted, when the cover element is moved to inoperative position, to be swung outwardly and downwardly to substantially horizontal position, in substantially flush relation with and constituting extensions of the table top, said hinge connections for each end panel including a pair of spaced apart bars projecting downwardly from the panel, through apertures in the table-like support, and adapted in one position to engage an abutment surface of the support to arrest the end panel in upright position, and adapted to engage another abutment surface of the support to arrest and dispose the end panel in substantially horizontal position, and means below the top for releasably latching said bars for supporting the end panels in upright position.

ANDREW H. GERHARDT.
